WITNESS:

Joseph M. Dabrowski, INVENTOR

Frank P. Neutromth
his ATTORNEY.

Patented July 17, 1928.

UNITED STATES PATENT OFFICE.

JOSEPH M. DABROWSKI, OF BROOKLYN, NEW YORK, ASSIGNOR TO MOORE BROTHERS COMPANY, OF NEW YORK, N. Y., A CORPORATION OF NEW YORK.

LIQUID-SOAP DISPENSER.

Application filed September 9, 1919. Serial No. 322,637.

My invention relates to liquid soap dispensers, and more particularly to a type thereof wherein a large supply of soap is stored in a reservoir and conveyed therefrom to a plurality of valve controlled discharge nozzles adjacent different wash basins, thus avoiding the waste and inconvenience incidental to the frequent refilling of a separate dispenser adjacent each basin.

While separate dispensers of the character above referred to are extensively used, there have heretofore been devised two types of dispensers employing a single reservoir and a plurality of nozzles, one of which employs a tank closed to atmosphere, and nozzles so constructed as to deliver or admit air to the tank with each actuation thereof, thus relieving the sub-atmospheric pressure which is developed in the tank by the withdrawal of soap therefrom and the other of which employs a similar tank, but depends for the feed of the soap upon air pressure within the tank. Expedients of this character have been found essential in this art mainly because of the substantially non-compressible nature of the material being handled, the necessity for segregating a small volume thereof and discharging it forcibly through a delivery nozzle, and the difficulty of preventing air vents in the delivery mechanism without resultant leakage and waste. There is also the difficulty that the flow of the soap to the dispensing valve mechanism must be sufficiently rapid to ensure the delivery of soap with quickly repeated actuations of said mechanisms.

With these conditions in mind, I have provided a liquid soap dispenser wherein a plurality of dispensing valve mechanisms are fed from one reservoir or tank, each of said mechanisms being so constructed that soap will flow freely by gravity to said mechanisms, such flow being interrupted with the actuation of the mechanism and being instantly resumed as the mechanism returns to normal. With a mechanism made in accordance with my invention, the tank is so vented as to always maintain atmospheric pressure therein, and no air flows through the distributing pipe system from the valves to the tank with a resultant delay in the resumption of the full flow of the soap after a charge has been delivered by said valve mechanism.

Furthermore, the valve mechanism is so constructed as to provide a valve controlled supply chamber of a capacity to afford a volume of soap adjacent the delivery valve sufficient for a number of charges, thus permitting quickly repeated actuations of this valve without likelihood of a failure to deliver soap with each actuation thereof. This chamber and the intake and delivery port therefrom are so arranged as to afford an air cushion of sufficient volume to permit the free movement of the valve, any reduction of pressure within this chamber resulting from forcible, positive ejection of the soap merely serving to increase the flow of the soap thereinto with the closing of the delivery, and the automatic opening of the feed, valve.

In a dispenser made in accordance with my invention, an ample supply of soap is always present adjacent each delivery mechanism so that all of said mechanisms may be actuated simultaneously without likelihood of a failure of any of them to deliver an adequate supply of soap.

The invention consists primarily in a liquid soap dispenser, embodying therein a tank having an opening thereon to atmosphere, distributing piping including a plurality of branch pipes, and a valve controlled delivery mechanism connected with each of said pipes consisting of a casing having a discharge nozzle, a partition having an intake port therethrough and forming a supply chamber adjacent said nozzle, a valve controlling said nozzle, an actuating stem therefor, a spring acting thereon, a second valve controlling said intake port, and operative connections between said valves whereby with the operation of said first named valve, said other valve will be closed, and with the closing of said first named valve, said other valve will be opened; and in such other novel features of construction and combination of parts as are herein-after set forth and described and more particularly pointed out in the claims hereto appended.

Referring to the drawings,

Fig. 1 is a view showing conventionally a dispenser made in accordance with my invention;

Fig. 2 is a longitudinal sectional view of one of the delivery mechanisms; and

Fig. 3 is a section on the line 3—3 of Fig. 2.

Like letters refer to like parts throughout the several views.

5 In the embodiment of my invention shown in the drawings, *a* indicates a reservoir or tank adapted to receive a considerable volume of liquid soap, the size of this tank of necessity varying to meet the requirements of different installations. Any suitable means for facilitating the charging of this tank may be provided, as the top *a'*, it being preferable to have the tank covered to exclude dust and dirt therefrom. The pressure within said tank, however, must be atmospheric, so that when I employ a cover, as shown, I provide a vent opening *a''* therein to the atmosphere.

20 Leading from the tank *a* is a piping including a main feed pipe *b* and the desired number of branch pipes *b'* leading therefrom, six such pipes being employed in the structure shown. There may be any desired number of such branch pipes, the proportioning of the size thereof and of the pipe *b* being a matter of secondary importance by reason of the small volume of soap which will be required at any one time. Ample capacity in the pipes should be provided however, because of the somewhat sluggish nature of liquid soap.

25 Each of the branch pipes *b'* has mounted on the end thereof, by means of any desired form of union, a valve controlled delivery mechanism adapted to deliver a small quantity of soap with each actuation thereof, said mechanism being so constructed as to prevent the flow of soap thereto from its branch pipe while soap is being delivered, 40 and to deliver soap upon quickly repeated actuations thereof, even though insufficient time between such actuations be afforded to permit a resumption of the flow of soap from the branch pipe into said mechanism. 45 Since each such delivery mechanism is like every other, a detailed description of but one of said mechanisms will be entered into.

50 The form of delivery mechanism shown in the drawings, comprises a casing *c* having a discharge nozzle *d* intermediate the ends thereof. Adjacent said nozzle *d*, I form within said casing a supply chamber *e* defined by a transverse partition *f*, and one 55 end of the bore of said casing, the distance between said end and said partition being such as to give the desired capacity to said chamber.

60 The end of said casing adjacent the partition *f* is open and communicates with a branch pipe *b'*, soap being admitted to the chamber *e* through a port *f'* in said partition. Said port preferably is towards the bottom of the partition to permit the formation of an air cushion in the upper part of

said chamber, without likelihood of the escape of air from said chamber to within the pipe *b'*.

65 The end of the chamber *e* adjacent the nozzle *d* is countersunk to form a sub-chamber *e'* comprising a short cylindrical portion terminating in a seat for a valve *g* of a diameter having a fairly close fit with said cylindrical portion. The passage through the nozzle *d* opens through said valve seat 70 towards the lower portion thereof.

75 The valve *g* is carried by a reciprocatory stem *g'* mounted in suitable bearings in the casing *c* and in the partition *f*, this stem having an enlarged head *g''* closing a spring chamber *c'* at one end of said casing. Acting between the end of said spring chamber and said enlarged head is a spring *h*, the function of which is not only to restore the valve mechanism to normal, but also to forcibly eject all or a substantial part of the soap admitted to the cylindrical portion of the casing, through the nozzle *d*, as the valve *g* is being seated. Beyond the enlarged portion *g''* the stem *g'* is provided with a push button *g''* having a facing of porcelain or other material which may be readily cleansed.

80 Slidably mounted on the valve stem *g'* is a valve comprising a rigid head *i* and a facing *i'* of flexible leather, rubber or other suitable material, adapted to seat against the partition *f* and close the port *f'* when the valve *g* is actuated to admit soap into the sub-cylindrical portion of the casing *e'*.

85 Acting between the valve *g* and the valve head *i* is a spring *j* of sufficiently light tension, or sufficiently short to normally permit the valve *i*—*i'* to be unseated under the pressure head within the branch pipe *b'*, while of sufficiently heavy tension or length to cause the seating of said valve with a slight opening movement of the valve *g*. By making the head *i* of smaller diameter than the facing *i'*, soap is permitted to pass said valve 90 during its closing movement to within the chamber *e*.

95 The construction described will also permit a substantially full closure of the valve *g* before the valve *i*—*i'* is permitted to open.

100 The operation of the herein described dispenser is substantially as follows:—

Assuming that an installation is just being put into service, the tank *a* is filled with liquid soap which flows freely through the distributing piping *b*, the various branch pipes *b'* and the open end of each casing *c*. The head pressure of the soap will unseat the valve *i*—*i'*, permitting the soap to flow through the port *f'* in the partition *f* to 110 within the chamber *e*.

115 Since at this time the valve *g* is closed, the air trapped in the chamber *e* will form a cushion towards the top thereof, thus affording a compressible medium which will 120

permit the free opening movement of the valve g . While the extent of this cushion will undoubtedly vary during a long use of the dispenser, it will always be sufficient to permit that displacement of the soap in the supply chamber e necessary to permit opening movement of the valve g .

When using the dispenser, the stem g' is pushed inwardly by means of the button g^3 and against the tension of the spring h , with the threefold effect of unseating the valve g , to open the passage of the nozzle d , and admit soap to within the sub-chamber e' (but without discharging soap through the nozzle d), and compressing the spring j so as to seat the valve $i-i'$ and close the port f' .

As the pressure on the button g^3 is relieved, the spring h will impart a quick return or outward movement to the stem g' and its valve g , trapping soap in the sub-chamber e' adjacent the nozzle d and forcibly ejecting it through said nozzle into the palm of the hand of the user.

The return of the valve g to normal, will relieve the spring j from compression, stresses therefrom so that substantially simultaneously with the seating of said valve, or instantly thereafter, the valve $i-i'$ will be unseated by the pressure from the soap within the pipe b' , and soap, to replace that delivered, will flow into the chamber e .

If the user should repeatedly push the button g^3 with a rapidity so great as to prevent the unseating of the valve $i-i'$ as described, soap will nevertheless be delivered with each actuation of the valve g , since the chamber e is of a capacity to supply a number of charges without being refilled from the tank a .

Should the air cushion be so reduced in volume as to have a tendency not to permit sufficient displacement of the soap in the chamber e , it is apparent that sufficient soap would be forced through the port f' into the pipe b' to afford the desired displacement space.

In order to secure the necessary rapidity of feed of the soap through the piping b and its branches b' , it is necessary that the tank a be open to the atmosphere, particularly as no air can enter said pipes through the delivery mechanism.

It is not my intention to limit the invention to the precise details of construction shown in the drawings, it being apparent that such may be varied without departing from the spirit and scope of the invention.

Having described the invention, what I claim as new and desire to have protected by Letters Patent, is:

1. A liquid soap dispenser embodying therein a tank having an opening therein to the atmosphere, distributing piping including a plurality of branch pipes and a valve controlled delivery mechanism con-

nected with each of said branch pipes consisting of a substantially horizontal casing, a substantially vertical partition having an intake port therethrough, and forming a horizontally extending supply chamber, one end of said chamber having a recessed portion forming a sub-chamber communicating with said supply chamber, a nozzle leading from said sub-chamber, a valve movable in said sub-chamber and controlling said nozzle, an actuating stem therefor, a spring acting thereon, a second valve seated within said supply chamber and controlling said intake port, and operative connections between said valves, whereby with the opening of said first named valve, said other valve will be closed, and with the closing of said first named valve, said other valve will be opened.

2. A liquid soap dispenser embodying therein a tank having an opening therein to the atmosphere, distributing piping including a plurality of branch pipes and a valve controlled delivery mechanism connected with each of said branch pipes consisting of a substantially horizontal casing, a substantially vertical partition having an intake port therethrough, and forming a horizontally extending supply chamber, one end of said chamber having a recessed portion forming a sub-chamber communicating with said supply chamber, a nozzle leading from said sub-chamber, a valve movable in said sub-chamber and controlling said nozzle, an actuating stem therefor, one end of which is mounted in a bearing opening in said partition, a spring acting on said valve, a second valve slidably mounted on said stem and controlling said intake port, and a spring seated between said valves, whereby with the opening of said first named valve, said other valve will be closed, and with the closing of said first named valve, said other valve will be opened.

3. A liquid soap dispenser embodying therein a tank having an opening therein to the atmosphere, distributing piping including a plurality of branch pipes and a valve controlled delivery mechanism connected with each of said branch pipes consisting of a substantially horizontal casing having a discharge nozzle, a substantially vertical partition adjacent one end of said casing forming a horizontally extending supply chamber adjacent said nozzle, and having an intake port adjacent the bottom thereof whereby air is prevented from flowing from said chamber into said branch pipe, a valve controlling said nozzle, an actuating stem therefor, a spring acting thereon, a second valve controlling said intake port, and operative connections between said valves, whereby with the opening of said first named valve, said other valve will be closed, and with the closing of said first named valve, said other valve will be opened.

4. A liquid soap dispenser embodying therein a tank having an opening therein to the atmosphere, distributing piping including a plurality of branch pipes and a valve controlled delivery mechanism connected with each of said branch pipes consisting of a casing having a discharge nozzle, a partition adjacent one end of said casing forming a supply chamber adjacent said nozzle, and having an intake port adjacent the bottom thereof whereby air is prevented from flowing from said chamber into said branch pipe, one end of said chamber having a recessed portion forming a sub-chamber communicating with said supply chamber, a valve movable in said sub-chamber and controlling said nozzle, an actuating stem therefor, a spring acting thereon, a second valve seated within said supply chamber and controlling said intake port, and operative connections between said valves, whereby with the opening of said first named valve, said other valve will be closed, and with the closing of said first named valve, said other valve will be opened.

5. A liquid soap dispenser embodying therein a tank having an opening therein to

the atmosphere, distributing piping including a plurality of branch pipes and a valve controlled delivery mechanism connected with each of said branch pipes consisting of a casing, a partition adjacent one end of said casing forming a supply chamber and having an intake port adjacent the bottom thereof whereby air is prevented from flowing from said chamber into said branch pipe, a recessed portion forming a sub-chamber communicating with said supply chamber, a nozzle leading from said sub-chamber, a valve movable in said sub-chamber and controlling said nozzle, an actuating stem therefor, one end of which is mounted in a bearing opening in said partition, a spring acting on said valve, a second valve slidably mounted on said stem and controlling said intake port, and a spring seated between said valves, whereby with the opening of said first named valve, said other valve will be closed, and with the closing of said first named valve, said other valve will be opened.

In witness whereof I have hereunto affixed my signature, this 26th day of August, 1919.

JOSEPH M. DABROWSKI.
